* cited by examiner

Primary Examiner — Susan Bennett Hattan*Assistant Examiner* — Janice Hallmark*(74) Attorney, Agent, or Firm* — Louis F. Teran(57) **CLAIM**

The ornamental design for a hookah with smoke purge valve and stem tube assembly, as shown and described.

DESCRIPTION

FIG. 1 is a perspective view of the hookah with smoke purge valve and stem tube assembly showing my new design;

FIG. 2 is a front view thereof;

FIG. 3 is a right side view thereof;

FIG. 4 is a rear view thereof; and,

FIG. 5 is a left side view thereof.

The broken lines in the drawings depict part of a hookah that form no part of the claimed design.
